(57) **CLAIM**

The ornamental design for a "utility knife handle," as shown and described.

DESCRIPTION

FIG. 1 is a front and right side perspective view of a utility knife handle, showing the front, right, and top sides of our new design;

FIG. 2 is a right side view of the utility knife handle shown in FIG. 1;

FIG. 3 is a left side view of the utility knife handle shown in FIG. 1;

FIG. 4 is a top plan view of the utility knife handle shown in FIG. 1;

FIG. 5 is a bottom plan view of the utility knife handle shown in FIG. 1;

FIG. 6 is a front view of the utility knife handle shown in FIG. 1;

FIG. 7 is a rear view of the utility knife handle shown in FIG. 1;

FIG. 8 is a right side perspective of the utility knife handle shown in FIG. 1, showing the knife blade folded into the utility knife handle;

FIG. 9 is a right side perspective view of the utility knife handle shown in FIG. 1, showing the knife blade in an alternate of removed position; and,

FIG. 10 is a broken elevational view of the utility knife handle without a blade portion attached.

The broken lines immediately adjacent the claimed areas represent the bounds of the claimed design while all other broken lines are directed to environment and are for illustrative purposes only; the broken lines form no part of the claimed design.
